(57) **CLAIM**

The ornamental design of a geometrical column unit, as shown and described.

DESCRIPTION

FIG. 1 is a front perspective view of a geometrical column, showing my new design;

FIG. 2 is a top side perspective view thereof;

FIG. 3 is a side elevational view thereof;

FIG. 4 is a top view thereof; and,

FIG. 5 is a bottom view thereof.

The new, original, and ornamental design of the geometrical column unit is contemplated to be a repeatable single segment capable of being stacked at the top and/or bottom surfaces to continue an unbroken/or broken surface pattern of the right, left, front and back sides.
